CLEANING-BRUSH

CROSS REFERENCE TO RELATED APPLICATION

This application is an improvement on the device of a related application entitled "CLEANING BRUSH," filed on July 12, 1967 by the same applicant as that of the present application and granted U.S. Pat. No. 3,421,171.

BACKGROUND OF THE INVENTION

This invention relates to a cleaning brush, and more particularly is directed to a cleaning brush which has bristles leaning in one direction for brushing and which is also provided with holding or gripping means for convenience in brushing.

The conventional brush has bristles disposed perpendicularly to the brush surface, accordingly it merely moves dust particles from one position to another when brushing, but it does not remove the dust particles from the surface being brushed.

SUMMARY OF THE INVENTION

This invention eliminates the inefficient cleaning of the conventional brush and provides a novel and improved cleaning brush which is easy to use and to carry.

According to one aspect of the present invention, there is provided a cleaning brush which has short bristles implanted so as to lean in one direction and comprises holding or gripping means for securing the brush surface and for making it possible to be convenient in brushing.

According to another aspect of the present invention, there is provided a cleaning brush characterized by the fact that the bristles are 1.7 mm. long, and are made of any fiber natural, synthetic or glass; the bristles are set at an angle with respect to the brush surface, said angle being from 3°-60°, preferably 60°-80°. According to the specific mode of brushing, any one of the following types of holding or gripping means, each having its respective advantage, can be taken up.

1. A holding means which comprises a handle and a brush surface comprising slanting bristles thereon.

2. A holding means as described in the above 1, the both sides of which is covered with short bristles, the handle extending in the same plane as the back.

3. A gripping means made from a hexahedron to the sides and bottom of which the bristles are bonded.

4. A gripping means made from two layers of synthetic leather, one of which is bonded to the base of the bristles, the sheath portion constructed by said two layers being able to receive a comb.

5. A gripping means made from two layers of synthetic leather, one of which is bonded to the base of the bristles, the other being bonded to the former on the perimeter and on a longitudinal line, constructing two sheath portions one being adapted to receive a comb and the other to receive a pencil respectively, a small sheath being provided on top of said comb-receiving portion for the purpose of receiving a nail file.

6. A holding means made from the layer of synthetic leather, thereon a holding band being secured so as to hold the brush on the fingers.

Therefore, one object of this invention is to provide cleaning brushes which may positively remove dust particles by easy operation.

Another object of this invention is to provide cleaning brushes which are convenient to carry and use.

In the cleaning brush in accordance with the present invention, the brush has a brush surface comprised of bristles implanted so as to slant in one direction for brushing; accordingly it removes perfectly the dust particles from the surface being brushed.

BRIEF DESCRIPTION OF THE DRAWINGS

FIG. 1-a is a perspective view of a cleaning brush with a holding means 1 as described above. FIG. 1-b is a lateral side view of the brush in FIG. 1-a.

FIG. 2-a is a perspective view of a cleaning brush with a holding means 2 as described above. FIG. 2-b is a longitudinal sectional view of the brush in FIG. 2-a. FIG. 2-c shows the frame of the brush of FIG. 2-a as dismembered and adapted to be assembled by means of one or more screws.

FIG. 3-a is a perspective view of a cleaning brush with a holding means 3 as described above. FIG. 3-b is a sectional view of the brush in FIG. 3-a.

FIG. 4-a with FIG. 4-b, FIG. 5-a with FIG. 5-b, and FIG. 6-a with FIG. 6-b, are views of the brushes with the gripping means 4, 5 and 6 as described above respectively.

DETAILED DESCRIPTION OF THE PREFERRED EMBODIMENT

15 Although specific embodiments of the invention have been selected for illustration in the drawings, and the following description is drawn in specific terms for the purpose of describing those embodiments of the invention, this description is not intended to limit the scope of the invention, which is defined in the claims.

16 Referring now to the drawings, which show six embodiments of this invention relative to the cleaning brush, they have a plurality of closely implanted short bristles which slant 25 with respect to the surface of the back thereof, as to the brush it will be hereinafter explained in detail.

17 In FIGS. 1-a and 1-b, the cleaning brush in accordance with the present invention comprises a brush surface 1, comprised of a plurality of short bristles 2 made of natural, chemical, 30 synthetic, or glass fibers, said bristles being closely spaced thereon and all leaning at the same angle in the same direction, and a gripping means including a handle 3 by which said brush is to be held. A suitable length for the bristles is 1-7 mm., and the angle of inclination thereof may be 3°-60°, but is 35 preferably 60°-80°. The short bristles comprising the brush surface can be secured to the holder 4 by means of back plate 5.

18 The brush as illustrated in FIG. 2-a, 2-b and 2-c, both sides of which are covered with short bristles of uniform diameter 40 and length slant in the same direction, provides the utility for enabling the cleaned stuff to be brushed without turning inside out.

19 The brush as shown in FIGS. 3-a and 3-b in which the brush surface is comprised of short bristles adhered to sides and bottom of a hexahedron 6, provides the improved efficiency for cleaning especially when used in a laundry owing to its solidity and easily-gripped form.

20 In FIGS. 4-a and 4-b, a brush with the holding means made 45 from two layers 6, 7 of synthetic leather, one of which is bonded to the bristles, is disclosed. A comb 8 can be received in the sheath portion constructed by said two layers, and is of use for preventing the bending of the leather, in brushing. It can be easily seen that the shape of this brush is so compact that it can be carried in a minimum space and that this construction also protects the comb from shock as well as from dust.

21 The brush as shown in FIGS. 5-a and 5-b, which is similar to the above described brush of FIGS. 4-a and 4-b in the construction of two layers, can receive, besides a comb 9, a pencil 10 and a nail file 11. This compact grooming set combines all the tools necessary for grooming and brushing in one easily carried kit.

22 FIGS. 6-a and 6-b discloses a brush with a holding means 55 made from the layer of synthetic leather 12, a holding band 13 being secured thereon so as to hold the brush on fingers.

23 The holding band 13 is made of thin synthetic leather which is secured on each side of the leather bonded to the brush surface. One or more fingers can be inserted into the space 70 formed between the layers of synthetic leather 12 and 13. This type of brush is suitable for fine brushing and effects brushing with a minimum of energy. It is suitable for carrying in a handbag or a cosmetics bag owing to its thin and yielding structure.

24 What is claimed is:

75 1. A cleaning brush comprising a brush surface with bristles;

a top layer and a bottom layer of synthetic leather, said bottom layer bonded to the said brush surface, the said top layer bonded to the perimeter of said bottom layer; the bristles of the said brush surface being 1-7 mm. in length and the inclined angle of said bristles to the brush surface being from 3°-80°.

2. A cleaning brush comprising a brush surface with bristles; a top layer and a bottom layer of synthetic leather, said bottom layer bonded to the said brush surface, the said top layer

bonded to the perimeter of said bottom layer; the bristles of the said brush surface being 1-7 mm. in length and the inclined angle of said bristles to the brush surface being from 3°-80°; said top layer forming two sheaths, one of said sheaths being adapted to receive a comb and the other of said sheaths to receive a writing instrument, and a small sheath provided on said comb-receiving sheath to hold a nail file.
